UNITED STATES PATENT OFFICE.

JOHN J. MCKANNA, OF HONESDALE, PENNSYLVANIA.

DESIGN FOR A CUT-GLASS VESSEL.

49,219.

Specification for Design.

Patented June 20, 1916.

Application filed April 15, 1916. Serial No. 91,497. Term of patent 3½ years.

To all whom it may concern:

Be it known that I, JOHN J. MCKANNA, a citizen of the United States of America, residing at Honesdale, in the county of Wayne and State of Pennsylvania, have invented a new, original, and ornamental Design for Cut-Glass Vessels, of which the following is a specification, reference being had to the accompanying drawings, forming a part thereof.

Figure 1 is a perspective view of a cut

glass vessel showing my new design. Fig. 2 is a fragmentary vertical sectional view of the same.

I claim:

The ornamental design for a cut glass vessel, as shown.

JOHN J. MCKANNA.

Witnesses:

L. WM. WAGNER,

ALBERT ROBERTS.
